UNITED STATES PATENT OFFICE.

WILLIAM SLEICHER, OF TROY, NEW YORK.

FURNACE-ROOF.

No. 895,051.

Specification of Letters Patent.

Patented Aug. 4, 1908.

Application filed February 26, 1908. Serial No. 417,944.

To all whom it may concern:

Be it known that I, WILLIAM SLEICHER, a citizen of the United States, residing at Troy, county of Rensselaer, and State of New York, have invented certain new and useful Improvements in Furnace-Roofs; and I do hereby declare the following to be a full, clear, and exact description of the invention, such as will enable others skilled in the art 10 to which it appertains to make and use the same.

The object of the invention is to improve the construction of furnace roofs, or roof portions, made up of a metallic frame or bung lined with, or supporting, a facing of refractory material to close the whole or a portion of the furnace top, and more particularly to provide a device of this type in which the refractory lining may readily be removed or 15 replaced, or its supporting mechanism may be adjusted to take up wear and, at the same time, provision may be made for the different coefficients of expansion of the metal parts and the refractory material, so that the 20 refractory material, is securely held in place at all temperatures.

The mechanism by which this object is accomplished will be understood from the following description and the accompanying 30 drawing.

In the drawing, Figure 1 is an elevation of the complete roof portion illustrating the improvements in their preferred form; Fig. 2 is an elevation of one end of the roof portion on a larger scale; Fig. 3 is a top plan view of the same; Fig. 4 is an end elevation of the same; and Fig. 5 is an end elevation of the metallic portion of the frame with the retaining devices removed.

The roof portion is made up of an arched metallic frame, which may be made of the shape in cross section shown in Fig. 5, so that it has a flat foot portion *a* against which the refractory material is held, and a stiffening 40 rib portion *a'*. The refractory material is preferably made up of a series of bricks *b* which are held against the arched under-surface of the metallic frame by the lever clamps *c*, pivoted to the ends of the stiffening rib *a'*, just above the foot portion *a* of the metallic frame. Near each end of the stiffening rib *a'* is formed an upstanding lug *d* having an opening adapted to receive one end of a pin *e*, the other end of which rests in a blind 50 socket in the upper end of the lever arm *c'* of the clamp *c* and is pivotally secured therein

by a split pin *f*. Screwed onto the end of the pin *e* inside of the lever arm *c'* is a nut forming an enlargement of the pin, and between this nut and the upstanding lug *d* is a coiled spring *g* which serves to normally press outward the upper end of the lever arm *c'*. In the arm *c'* between its pivot and its upper end is an internally screw-threaded boss into which is screwed a set-screw *h*, the inner end of which rests in an elongated socket *k* on the end of the stiffening flange *a'*. This set screw serves as an adjustable spacing member between the lever arm *c'* of the pivoted clamp and the end of the stiffening flange *a'*.

The operation is as follows: When it is desired to fit a lining to the under surface of the metal frame, a series of bricks of refractory material are laid on edge along the under surface of the foot piece *a* between the clamps *c* and when this series of bricks has been completed from one end of the frame to the other, the set screws *h* are turned until they engage their sockets and until by their movement 80 the clamps are turned on their pivots to tightly clamp the refractory lining in place, so that the lining is positively held by the clamps, which, on account of the set screws, have no capacity for turning on their pivots 85 in such a direction as to loosen the bricks constituting the lining. It will be understood that when this operation is performed the metallic frame is in a relatively cool state. When the roof portion has thus been completed, it is placed in proper position on the furnace and as it heats up the metal will expand, the coefficient of expansion of the metal being considerably greater than that of the refractory material, which may even 90 have a negative coefficient of expansion, so that it contracts with the heat. The expansion of the metal frame will elongate it so that the points at which the clamps are pivoted move in a direction to loosen the bricks 100 which have not expanded to so great an extent. When this takes place the spring comes into play and by its expansion turns the clamp on its pivot and holds the clamping face tightly against the end of the brick. Upon 105 the cooling of the roof portion the metal contracts to its original dimensions and the parts assume their original positions, the ends of the set screws again engaging their sockets.

It will be observed that by this construction the lining of refractory material is positively held in place under normal conditions 110

by the unyielding spacing members and the spring is in no way depended upon for that purpose. It is only when the metal expands to a greater extent than the refractory material that the spring has any effect at all. The result is that the retaining means are entirely reliable and yet have sufficient flexibility to compensate for the difference in the coefficients of expansion of the two metals of

10 which the roof portion is made up.

What I claim is:

1. A furnace roof-member having a metallic frame, a lever-clamp pivoted thereto and having a depending member adapted to clamp a facing of refractory material beneath the metallic frame, and a spring co-acting with the lever-arm to force the depending member of the clamp yieldingly against the refractory material, whereby the 15 clamping action on the refractory material is automatically maintained as the frame expands, in combination with a supplemental adjustable and unyielding spacing member for positively forcing the depending member 20 of the clamp into clamping position; substantially as described.

2. A furnace roof - member having an arched metallic frame, a lever-clamp pivoted to each end thereof, each lever-clamp having 25 a depending member to clamp between them an arched body of refractory material, a spring co-acting with the lever arm of each clamp

to force the depending member yieldingly against the refractory material, whereby the clamping action on the refractory material 35 is automatically maintained as the frame expands, in combination with a supplemental adjustable and unyielding spacing member associated with each clamp for positively forcing the depending member into clamping 40 position; substantially as described.

3. In a furnace-roof-member the combination with an arched metallic frame, of a lever clamp comprising a depending member *c* and a lever arm *c'* pivoted to each end of the metallic frame and adapted to clamp between them an arched body of refractory material, a set-screw *h* passing through each lever arm and engaging a socket in the adjacent end of the metallic frame for positively forcing the 45 depending-members into clamping position, and a coiled spring *g* supported between the upper end of each lever-arm and a fixed abutment on the metallic frame for causing the depending members of the clamps to retain 50 the refractory material as the metallic frame expands; substantially as described.

In testimony whereof I affix my signature, in presence of two witnesses.

WILLIAM SLEICHER.
